UNITED STATES PATENT OFFICE.

BURTRON G. HUTTON AND RAYMOND M. HUTTON, OF PHILADELPHIA, PENNSYLVANIA.

KNOCKDOWN CRATE.

967,923.

Specification of Letters Patent. Patented Aug. 23, 1910.

Application filed February 2, 1910. Serial No. 541,497.

To all whom it may concern:

Be it known that we, BURTRON G. HUTTON and RAYMOND M. HUTTON, citizens of the United States, residing at Philadelphia, in the county of Philadelphia and State of Pennsylvania, have invented certain new and useful Improvements in Knockdown Crates, of which the following is a specification.

10 Our invention relates to improvements in knockdown crates, the object of the invention being to provide an improved crate of this character, which can be quickly knocked down when empty, and which will inclose 15 the separating partitions between the articles normally carried by the crate, and may be returned, and in shipment occupy but a comparatively small space.

A further object is to provide a crate 20 which may be quickly erected from its knock down form, and which will be securely and strongly held in its built up shape, so as to thoroughly protect the contents of the crate, and provide improved 25 mechanism for locking the crate in this built up and knocked down form.

A further object is to provide an improved crate of this character, which is extremely simple in construction, cheap to 30 manufacture, yet strong and durable in use.

With these and other objects in view, the invention consists in certain novel features of construction, and combinations and arrangements of parts as will be more fully 35 hereinafter described and pointed out in the claims.

In the accompanying drawings, Figure 1 40 is a perspective view illustrating our improved crate in built up form with the cover thrown back. Fig. 2, is a view in longitudinal section with the cover in closed position. Fig. 3, is a view in cross section of Fig. 2. Fig. 4, is an enlarged view in cross section at the center of the crate illustrating the cover latch. Fig. 5, is a detail perspective view of one of the corner angles. Fig. 6, is a detail perspective view of one 45 of the sleeved brackets. Fig. 7, is a perspective view of the crate in knocked down form. Fig. 8, is a view in longitudinal section of Fig. 7. Fig. 9, is a view in cross section of Fig. 8. Fig. 10, is a view of the latch keeper, and Fig. 11, is a view of the latch.

50 The crate may be made of wood, metal or any suitable material, and we do not there-

fore limit our invention to any particular material of which the several parts are made.

The crate comprises a bottom 1, to which 60 strips 2, 2, are secured at right angles, and extend upward from the ends of the bottom forming small sections of the ends of the crate.

To the front and rear edges of bottom 1, 65 strips 3 are secured, and disposed at right angles to the bottom and to the strips 2, forming a box-like rigid structure, and it will be noted that the front strip 3 extends upward slightly higher than the back strip 70 4, and both of the strips 3 and 4 extend higher than do the end strips 2, the purpose of which will hereinafter appear when describing the knockdown features of the casing. 75

To the end strips 2 the crate ends 5 are connected by hinges 6, said hinges being located on the inside of the crate. To the front and back strips 3 and 4, the crate front 7 and back 8 are connected by hinges 6, and 80 hereinafter in the description, the same reference character 6 will be used to indicate all of the hinges of the same type, this is the ordinary leaf hinge illustrated.

To the bottom 1, and midway the length 85 of the bottom, a transverse partition 9 is connected by hinges 6, and it will be noted particularly by reference to Fig. 2, that this partition 9 when in a vertical position, is appreciably shorter than the sides and ends 90 of the crate, so as not to interfere with the operation of a stay rod 10 above the same. There are three of these stay rods 10 employed, one being located at the center above partition 9, and the other two adjacent the 95 ends of the crate just inside of ends 5 and near the upper edges of the crate. These stay rods have their downwardly bent ends mounted so as to swing in sleeved brackets 11 secured to back 8, and their free ends are 100 adapted to engage in eyes 12 on front 7.

The brackets 11 are made with elongated sleeves so as to prevent any downward pivotal movement of the stay rods with relation to the back 8, and hence maintain 105 them always in their normal position, either across the crate when the latter is in built up form, or over against the back 8 when the crate is to be knocked down.

To the front 7 and back 8 at their ends, 110 metal angles 13 are secured and are adapted, as shown in Fig. 1, to overlap the ends 5,

when the crate is in built up form, and prevent the ends from swinging outward. These ends are preferably recessed as shown at 24 to receive the fingers of the person handling the same, and the ends are reinforced by bars 14 secured at their upper edges, which bars also serve as handholds to facilitate the manipulation of the crate.

15 represents the cover of the crate, which 10 is connected by three-wing hinges 16 with back 8. These hinges 16, which I refer to as three-wing hinges are provided with three wings or plates, which have pivotal connection with each other, so that in the normal 15 operation of the cover, one of these pivotal connections is operated, while when the crate is knocked down, the intermediate wing of the hinge enables the cover to be swung backward to accommodate itself to the dimensions of the knockdown crate, as will hereinafter appear.

On the inside of front 7 at its center, and adjacent its upper edge is a keeper 17, which is of metal and provided at its upper end 25 with a heart shaped recess 18, the upper end of the keeper being beveled as shown at 19, to direct the members of a spring latch 20 into the heart shaped recess. The spring latch 20 is secured to the under face of top 30 15, and is preferably in the form of a wire spring coiled between its ends, the ends of the spring adapted to engage the beveled shoulders 19 and compress the members toward each other, and then spring into the 35 heart shaped recess 18 to hold the cover in closed position.

The crate in normal operation is adapted to contain on each side of partition 9, a plurality of removable partitions or spacers in 40 accordance with the articles carried in the crate, and while the crate is especially designed for eggs, it is in no wise limited to such use.

To knock down the crate, the stay rods 45 10 are raised at their free ends to free them from eyes 12 and the rods are then swung back against back 8. Partition 9 is then folded down on bottom 1, and the removable partitions of the crate illustrated at 21, are 50 piled on the bottom and the ends 5, 5, folded in upon them. The back 8 is then folded down upon ends 5, 5, and cover 15 is thrown back. The triple wing hinges 16 permit this movement, so that the cover 15 will lie 55 flush with the rectangular formation of the crate. The front 7 is then swung down on

cover 15, and it will be noted that the angles 13 of front 7 are provided with small recesses 22, which are adapted, when the crate is knocked down to engage over pins 23 on back 8, and thus hold the crate in this knocked down form, requiring a considerable pull on the front 7 to pull it up when the crate is once knocked down, thus serving as a lock to hold the crate in knocked down shape and its contents within the same for its return shipment.

Various slight changes might be made in the general form and arrangements of parts described without departing from our invention, and hence we do not restrict ourselves to the precise details set forth, but consider ourselves at liberty to make such changes and alterations as fairly fall within the spirit and scope of the claims.

Having thus described our invention what we claim as new and desire to secure by Letters Patent is:—

1. In a knockdown crate, the combination with a bottom, of strips secured to all edges 80 of the bottom forming a receptacle, ends, front and back hinged to said strips, and adapted to be folded inward, a top, double hinges connecting the top and back, stay rods pivotally secured at one end to the back, eyes on the front, hooked ends on the stay rods engaging in said eyes, and angles secured to the front and back and engaging over the outside of the ends.

2. In a knockdown crate, the combination with a bottom, of strips secured to all edges 90 of the bottom forming a receptacle, ends, front and back hinged to said strips, and adapted to be folded inward, a top, double hinges connecting the top and back, stay rods pivotally secured at one end to the back, eyes on the front, hooked ends on the stay rods engaging in said eyes, angles secured to the front and back and engaging over the outside of the ends, pins on the 100 ends of the back, and said angles having recesses to receive the pins and hold the parts in knockdown formation.

In testimony whereof we have signed our names to this specification in the presence 105 of two subscribing witnesses.
